SUCTION SWEEPER AND MOP

Albert Herman, New York, N. Y.

Application May 14, 1937, Serial No. 142,527

3 Claims. (Cl. 15—10)

This invention relates to new and useful improvements in a suction sweeper and mop.

More specifically, the invention proposes the construction of a suction sweeper and mop which is characterized by the provision of a flat body having an elongated mopping unit extended longitudinally of the body on the bottom thereof and at one end connected with an elbow which extends through an end portion of the body and connects with a motor driven fan for providing suction to draw the dirt from the mopping unit.

Still further the invention provides for a plurality of bristles which are to be mounted on the bottom side of the flat body and around the elongated mopping unit to assist the mopping unit in the cleaning action.

Still further the invention provides that the elongated mopping unit be pivotally mounted upon and transversely of the flat body so that it may be adjusted to operate on a bias to better clean the surface over which it is being passed.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

30 Fig. 1 is a plan view of a suction sweeper and mop constructed according to this invention.

Fig. 2 is an end elevational view of Fig. 1.

Fig. 3 is a bottom plan view of Fig. 1.

35 Fig. 4 is a perspective view of the elongated mopping unit, per se.

Fig. 5 is a view taken on the line 5—5 of Fig. 4.

Fig. 6 is a view taken on the line 6—6 of Fig. 1.

Fig. 7 is a view taken on the line 7—7 of Fig. 1.

40 Fig. 8 is a view taken on the line 8—8 of Fig. 7.

Fig. 9 is a view taken on the line 9—9 of Fig. 1.

The suction sweeper and mop, according to this invention, comprises a flat body 10 having a handle 11 by which the body may be moved. A motor driven fan 12 is mounted on the top of the body 10 and upon one portion thereof and is provided with a discharge bag 13 connected therewith and rested upon the top of the body 10 on another portion thereof. An elbow 14 is connected with

50 the suction end of the fan 12 and extends through an end opening 10a in the body 10 to the bottom side thereof. An elongated mopping unit 15 extends longitudinally of the body 10 on the bottom thereof and at one end is connected with the elbow 14. A plurality of bristles 16 are mounted

on the bottom of the body 10 along the sides of the mopping unit 15.

The flat body 10 comprises a piece of wood or other material of substantially oval shape which is provided with an opening 10b into which a portion of the casing 12a of the fan 12 may engage in order to properly position the fan body on the flat body 10. The bag 13 is connected to an outlet 12b formed on one side of the casing 12a so that the dust and dirt drawn into the casing 12a by the rotative motion of the fan 12 will be forced through the outlet 12b and into the bag 13. The elbow 14 has one of its ends 14a extending into an opening 12c formed in the front face of the casing 12a to draw the dust and dirt from the mopping unit 15 into the casing 12a.

The handle 11 has one of its ends 11a pivotally mounted between a pair of lugs 17 which are fixedly mounted upon the flat body 10 by means of fastening elements 18. The other end of the handle 11 is provided with a switch 19 which is arranged so that it may control the motor 12d which rotates the fan 12. An electric cord 20 is provided with a plug 21 which may be plugged into an ordinary house outlet. The cord 20 extends into the handle 11 and contacts the switch 19 and then extends down through the handle coming out at the bottom thereof and continuing into the casing 12a where it connects with the motor 12d to operate the fan 12 when the switch is pivoted to its "on" position.

The elongated mopping unit 15 comprises a top portion 15a which is adapted to abut the bottom face of the flat body 10. Near the edges of the top portion 15a there is a depending flange portion 15b which is soldered or in any other manner attached to the bottom face of the top portion 15a. A second top portion 15c is attached to the bottom face of the top portion 15a and is provided with a depending flange portion 15d located within the flange 15b forming a channel between the adjacent flanges 15b and 15d. The depending flange 15d is integrally formed with the second top portion 15c which in turn is soldered or in any other similar manner securely attached to the top portion 15a. A plurality of felt elements 22 are engaged between the depending flanges 15b and 15d and a plurality of bolts 23 are engaged through the flange 15b, the felt elements 22, and the inner flange 15d to form a rigid unit of these elements.

The ends of the outer flange 15b are directed away from the felt elements 22 and have their faces abutting one another so that a bolt 24 may be passed therethrough to act as a clamp for

holding the felt elements 22 in position between the flanges. Near the end of the top portion 15^a an opening 25 is provided which extends through the top portion 15^a and the second top portion 15^c. 5 A collar 26 is attached to the top face of the top portion 15^a and is adapted to encircle the opening 25. This collar 26 then extends into the free end of the elbow 14 in order to convey dust and dirt from the mopping unit 15 to the casing 12^a.

10 A means is provided for pivotally mounting the mopping unit upon the bottom face of the flat body 10 so that it may be pivoted to permit it to operate on a bias to better clean the surface over which it is being passed. This means comprises a wing nut 27 which passes through an opening 14^b in the elbow 14 and through an elongated longitudinal slot 26^a formed in the collar 26 for pivotally mounting the front end 15 of the mopping unit on the flat body 10. The bristles 16 on the bottom face of the flat body 10 are spaced away from the mopping unit 15 to permit the mopping unit to be pivoted with relation to the flat body 10. The rear end of the mopping unit is provided with a screw 28 which passes through a slot 10^c formed in the flat body 10 and which threadedly engages an opening 29 in the top portion 15^a in order to permit the lower end of the mopping unit 15 to be rigidly held upon the flat body in any of the adjusted positions of the front end of this mopping unit. Since the suction inlet is located at one end of the mopping unit 15 it is difficult to draw the dirt from the end of the mopping unit opposite the suction inlet and therefore when the mopping unit operates on a bias it will direct the dirt towards the suction inlet where it will be easily possible for the suction from the motor 12 to pick it up.

40 It is to be understood that the shape and size of the body 10 may be changed as desired and the various parts will be altered correspondingly to permit the device to be used for different floor surfaces. The handle 11, and switch 19 may be of any preferred style. The switch may 45 also be of the speed control type to vary the speed of the motor.

Any suitable covering device may also be used to cover the various parts and mechanisms mounted on the body 10. This cover may be 50 of suitable hard substance and ornamented as desired.

This present invention sweeps and mops the floor and collects the dust and dirt all with one action eliminating the shaking of dusty mops out of open windows.

55 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I 60 claim as new, and desire to secure by United States Letters Patent is:

1. In a suction sweeper and mop, a flat body

having a suction device mounted thereon with a downwardly projecting inlet extending through an opening therein, bristles mounted around the periphery of the bottom face of said flat body, and an elongated hollow mopping unit having a floor contacting suction mouth on the bottom face of said flat body between said bristles and having one of its ends pivotally attached to the inlet of said suction device so that said mopping unit may be pivoted in a horizontal plane relative to said flat body so as to operate on a bias with relation to the direction in which the device is being moved to direct the dust and dirt from the other end of said mopping unit toward the said pivoted end where it will be convenient for 15 said suction device to pick it up.

2. In a suction sweeper and mop, a flat body having a suction device mounted thereon with a downwardly projecting inlet extending through an opening therein, bristles mounted around the periphery of the bottom face of said flat body, and an elongated hollow mopping unit having a floor contacting suction mouth on the bottom face of said flat body between said bristles and having one of its ends pivotally attached to the 20 inlet of said suction device so that said mopping unit may be pivoted in a horizontal plane relative to said flat body so as to operate on a bias with relation to the direction in which the device is being moved to direct the dust and dirt from the other end of said mopping unit toward the 25 said pivoted end where it will be convenient for said suction device to pick it up, said pivotal mounting of said mopping unit comprising a collar on said mopping unit extending into said 30 suction inlet and a wing nut extending through an opening in said suction inlet and through an elongated slot in said collar for pivotally mounting one end of said mopping unit.

3. In a suction sweeper and mop, a flat body 40 having a suction device mounted thereon with a downwardly projecting inlet extending through an opening therein, bristles mounted around the periphery of the bottom face of said flat body, and an elongated hollow mopping unit having 45 a floor contacting suction mouth on the bottom face of said flat body between said bristles and having one of its ends pivotally attached to the inlet of said suction device so that said mopping unit may be pivoted in a horizontal plane relative to said flat body so as to operate on a bias with relation to the direction in which the device is being moved to direct the dust and dirt from the other end of said mopping unit toward the 50 said pivoted end where it will be convenient for said suction device to pick it up, said pivotal mounting of said mopping unit comprising a collar on said mopping unit extending into said 55 suction inlet and a wing nut extending through an opening in said suction inlet and through an elongated slot in said collar for pivotally mounting one end of said mopping unit, means for adjustably holding the other end of said mopping unit so that it may be adjusted with relation to the pivoted end of said mopping unit. 60

ALBERT HERMAN.
